UNITED STATES PATENT OFFICE.

FREDRICK MONIER, OF NEWARK, NEW JERSEY.

BRIDLE-BIT.

SPECIFICATION forming part of Letters Patent No. 357,683, dated February 15, 1887.

Application filed August 13, 1886. Serial No. 210,764. (No model.)

To all whom it may concern:

Be it known that I, FREDRICK MONIER, a citizen of the United States, residing at Newark, in the county of Essex and State of New Jersey, have invented certain new and useful Improvements in Bridle-Bits; and I do hereby declare that the following is a full, clear, and exact description of the invention, such as will enable others skilled in the art to which it applies to make and use the same.

This invention relates to improvements in bits, particularly those known as "Mexican" bits, and refers more specifically to the mouth-piece thereof, the object of the invention being to secure greater strength in the said mouth-piece, and at the same time to provide a more powerful bit, which gives to the rider more perfect control over the horse, because of the increased leverage afforded by the peculiar construction of the bit.

Figure 1 in the drawings illustrates the construction of the improved bit, and Figs. 2 and 3 are detail views of the link or port.

In said view A and A' indicate the cheek-pieces, and a a' the side portions of the mouth-piece. Between said side portions of the mouth-piece is a link, projecting on each side of the line of the portions a a', forming rounded projections b b'. Within the longer of said projections a roller, c, may be arranged, as shown. The said link is preferably cast or wrought integrally with the side portions of the mouth-piece. By thus extending the link oppositely on each side of the side portions much greater leverage is obtained, both of said projections engaging with the inside of the mouth of the horse, the longer projection, b, striking the roof of the mouth, and the projection b' the lower part thereof. Thus a double "purchase" or leverage is secured, which gives to the rider much greater control of the horse than can otherwise be obtained. The said oppositely-projecting portions b b' may lie in the same plane, as indicated in Figs. 1 and 2, or the shorter projection, b', may be bent downward, as in Fig. 3, to give greater power to the bit.

I am fully aware that bits have been devised having a solid plate extending oppositely in a straight line on each side of the mouth-piece. Such a construction is shown in Patent to Roberts, No. 31,557, and to such I waive all claim;

but in my improved mouth-piece the projecting port is provided with an opening, d, therein, only sufficient metal being left to secure the requisite strength. This construction is advantageous in that it enables a roller, c, to be arranged therein, which eases the mouth of the horse; and, furthermore, the opening permits the saliva to moisten the tongue of the horse, whereas the solid plate prevents the free access of the saliva thereunder, and in consequence the tongue is liable to become parched and sore.

I am also aware that a mouth-piece for a bit provided with oppositely-projecting portions having an opening therein is shown in the Patent No. 345,051; but the said opening is very much larger than the opening d in my improved mouth-piece, being about the width of the tongue of a horse, and is intended to prevent the protruding or lolling of the horse's tongue, while the opening d in my mouth-piece is only wide enough to receive the roller c, being long and narrow, and to permit the free flow of the saliva under the port, as above mentioned.

As will be evident, the mouth-piece may be inserted in the cheek-pieces, so that the bent portion b' may incline upward or downward, according to the disposition of the horse by whom the bit is to be used, some requiring all the power that can be brought to bear in the mouth to restrain them—for instance, mustangs, for whom the bit is principally intended—while others can be held with much less power, but yet require more purchase than is provided by the portion b of the port alone. With an unruly horse the portion b' may be bent, as is indicated in Fig. 3, to act most positively, while with a comparatively gentle horse the same mouth-piece may be used; but the same is inserted in the cheek-pieces in such a manner that the bent portion inclines upward, instead of downward, the reverse of that shown in Fig. 3. Thus the same mouth-piece answers a double purpose, accordingly to its arrangement in the cheek-pieces, the main portion of the port remaining the same in the mouth of the horse.

To avoid any injury to the mouth of the horse, the portion b' of the port is much shorter than the upper portion, b, being about one-third thereof, as indicated in Fig. 1, thus ac-

commodating itself to the conformation of the mouth of the horse, which permits the use of the long portion, *b*, striking against the hard roof thereof, securing thereby the increased leverage without any injury resulting therefrom. As the short portion, *b'*, lies directly upon the tongue but little force is necessary to secure the desired pressure; hence a long projection beneath the mouth-piece is injurious, and is liable to make the tongue sore.

Having thus described my invention, I desire to claim the following:

1. In a bit, a mouth-piece provided with a port formed integrally therewith, consisting of the long and short portions, *b b'*, projecting oppositely from said mouth-piece and provided with a long narrow opening, *d*, therein, for the purposes set forth.

2. In a bit, a mouth-piece provided with a port formed integrally therewith, projecting oppositely on each side of and at right angles to said mouth-piece and provided with an opening, *d*, therein, one of said oppositely-projecting portions of the port, as *b'*, being bent at an angle to the other of said oppositely-projecting portions, as *b*, said portion *b* being provided with a collar or wing, *c*, arranged in the opening therein, substantially as and for the purpose set forth.

In testimony whereof I have hereunto set my hand this 11th day of August, 1886.

FREDRICK MONIER.
